UNITED STATES PATENT OFFICE.

JOHN R. WARREN, OF GRAND RAPIDS, MICHIGAN, ASSIGNOR TO SAID JOHN R. WARREN, DONALD J. CAMPBELL, OF MUSKEGON HEIGHTS, MICHIGAN, CHARLES E. JOHNSON, PAUL R. BEARDSLEY, AND CARL P. DAMM, ALL OF MUSKEGON, MICHIGAN, TRUSTEES.

ENGINE.

Application filed June 20, 1921. Serial No. 478,797.

To all whom it may concern:

Be it known that I, JOHN R. WARREN, a citizen of the United States, residing at Grand Rapids, in the county of Kent and State of Michigan, have invented new and useful Improvements in Engines, of which the following is a specification.

The present invention relates to engines; and its object is, generally, to provide an improved valve mechanism wherein a rotary valve, although sufficiently tight to prevent leakage, shall not be subject to binding and sticking occasioned by heating or otherwise; and further and more particularly, to provide a one-piece valve-casing for the rotary valve whereby said end may be attained; and further, to provide a one-piece cylinder and valve-casing; and further, to provide improved and economical methods 20 for constructing such parts.

These and any other objects hereinafter appearing are attained by, and the invention finds preferable embodiment in, the structure particularly described in the body of this specification and illustrated by the accompanying drawings, in which:

Figure 1 is a side view of an internal-combustion engine to which my valve mechanism is applied, certain parts being broken 30 away;

Figure 2 is a transverse sectional view thereof taken on a vertical plane corresponding to line 2—2 of Figure 1;

Figure 3 is a view in perspective of a 35 bushing or sleeve surrounding the valve;

Figure 4 is a side view of a block or member comprising three of the engine's cylinders and the valve-casing; and

Figure 5 is an end view of the same.

In the embodiment of my invention chosen for illustration by the drawings and for detailed description in the body of this specification, the invention is shown in connection with a four-cycle type internal-combustion engine having six cylinders, 1, 2 and 3 thereof appearing in diametrical longitudinal section in Figure 1. These cylinders have pistons 4, 5, 6 furnished with connecting rods 7, 8, 9 for operating the cranks 10, 11, 12 respectively, on the crank shaft or engine shaft 13. At their upper ends, the

cylinders have ports 14, 15, 16 respectively for admitting the operating fluid thereinto and for expelling the products of combustion therefrom. The rotary valve 17 for controlling such admission of the fluid to the cylinders and for permitting the expulsion of such products therefrom rotates in a bearing or valve chamber in a valve-casing, designated generally 18, having ports 60 communicating with the cylinders through their ports 14, 15, 16 respectively. This valve-casing and the three cylinders are in the construction illustrated all comprised in a one-piece block or member 20, as particularly shown in Figure 2, the valve-casing part of said member being split at one side—at 21—to form a valve-casing portion 22 adjacent the cylinders and another valve-casing portion 23 remote therefrom which 70 is secured to the frame 24 of the engine as by bolts 25, said valve-casing portions adjacent the gap or split 21 being thus slightly separated. Inasmuch as the lower part of the block or member 20 comprising the cylinders and the valve-casing portion 22 has a slight longitudinal movement relatively to the frame 24 and valve-casing portion 23, (permitted by said separation of the casing portions at the gap or split 21 and by the 80 resiliency of the metal of which said member or block is formed) it will be seen that the pressure in the cylinders tightens the valve casing on the valve. As shown, means are provided to prevent leakage between the 85 valve-casing portions 22 and 23 at said gap or split 21, such means being preferably a bushing or sleeve 26 contained in the valve-casing and surrounding the rotary valve and extending over said gap or split 21. 90 This bushing has openings 27 which register with the cylinders' ports respectively. To provide for the expanding and contracting of the bushing, a series of slits 28 are cut therethrough has shown in Figure 3. 95

The valve 17 is hollow, having longitudinally extending passages 29, 30 to which the fluid is supplied from a vent 31 in the block or member 20, the fluid thence passing through a series of inlets 32 through the 100 valve's wall and to each cylinder's port through diametrically opposite openings 33,

34, in the valve's wall, the products of combustion being discharged from each cylinder through diametrically opposite outlets 35, 36 through the valve's wall and into 6 the longitudinally extending passages 37, 38 opening at the ends of the valve into exhaust pipes 39. These inlets, openings and outlets through the valve's wall are so disposed angularly of the valve that the sequence of supply to and exhaust from the several cylinders is properly timed.

As shown in Figure 1, the engine's crank shaft carries a skew gear 40 meshing with a skew gear 41 on the vertical shaft 42 between the third and fourth cylinders, said shaft having a skew gear 43 meshing with a like gear 44 driving the rotary valve 17. The cylinders and valve-casing portions 22 and 23 have a continuous water jacket 20 formed in the block or member 20, the water-containing space being designated 45, water being supplied by the pipe 46 and discharged by the pipe 47. A siphon pipe 50 for drawing the water from the interior 25 of the valve-casing portion 23 and an air pipe 51 are shown in Figure 2. Openings for the cylinders' spark plugs are indicated at 52 and a lubricating wick is shown at 53.

It will be seen that the valve-casing portions 22, 23 being formed in one piece, and the cylinders being also preferably formed in one piece therewith as shown, the whole may be very economically manufactured as 30 a single casting, properly machined or bored, and the gap or split 21 may be made by sawing through the metal; and that, thus formed, the interrelative position of the parts—cylinders and valve-casing portions—are fixed and cannot become inter- 35 relatively out of adjustment.

Additional means for securing the block or member 20 to the frame 24 are provided by the bolts 54.

In the construction illustrated, the cylinders move longitudinally in guide bearings 55 on the frame 24. Inasmuch as the upper valve-casing portion 23 is rigidly secured to the frame as by the bolts 25 adjacent the gap or split 21, I provide a resilient portion 40 of the block intermediate the cylinders and the valve-casing by forming said portion reduced in cross section at 56 as shown in Figure 2.

The invention being intended to be pointed out in the claims, is not to be limited to or by details of construction of the particular embodiment thereof illustrated by the drawings or hereinbefore described.

I claim:

1. In an engine; a frame; a member comprising a cylinder longitudinally movable relatively to the frame and comprising also a one-piece split valve-casing secured to the

frame and having a port communicating with the cylinder; a valve rotatable in said valve-casing and adapted to open and close said port.

2. In an engine; a frame; a member comprising a cylinder longitudinally movable relatively to the frame and comprising also a one-piece valve-casing having a port communicating with the cylinder and being split to form a valve-casing portion adjacent the cylinder and another valve-casing portion which is secured to the frame; a valve rotatable in said valve-casing and adapted to open and close said port.

3. In an engine; a frame; a one-piece member comprising a cylinder longitudinally movable relatively to the frame and comprising also a valve-casing having a port communicating with the cylinder and being split to form a valve-casing portion adjacent the cylinder and another valve-casing portion which is secured to the frame; a valve rotatable in said valve-casing and adapted to open and close said port.

4. In an engine; a frame; a member comprising a cylinder longitudinally movable relatively to the frame and comprising also a one-piece valve-casing having a port communicating with the cylinder and being split to form a valve-casing portion adjacent the cylinder and a valve-casing portion remote therefrom which is secured to the frame; a valve rotatable in said valve-casing and adapted to open and close said port.

5. In an engine; a frame; a member comprising a cylinder longitudinally movable relatively to the frame and comprising also a one-piece split valve-casing secured to the frame and having a port communicating with the cylinder; a valve rotatable in said valve-casing and adapted to open and close said port; a bushing between the valve and valve-casing extending over the split in the valve-casing and having an opening registering with said port.

6. In an engine; a frame; a member comprising a cylinder longitudinally movable relatively to the frame and comprising also a one-piece valve-casing having a port communicating with the cylinder and being split to form a valve-casing portion adjacent the cylinder and another valve-casing portion which is secured to the frame; a valve rotatable in said valve-casing and adapted to open and close said port; a bushing between the valve and valve-casing extending over the split in the valve-casing and having an opening registering with said port.

7. In an engine; a frame; a one-piece member comprising a cylinder longitudinally movable relatively to the frame and comprising also a valve-casing having a port communicating with the cylinder and being split to form a valve-casing portion adja-

cent the cylinder and another valve-casing portion which is secured to the frame; a valve rotatable in said valve-casing and adapted to open and close said port; a bushing between the valve and valve-casing extending over the split in the valve-casing and having an opening registering with said port.

8. In an engine; a frame; a member comprising a cylinder longitudinally movable relatively to the frame and comprising also a one-piece valve-casing having a port communicating with the cylinder and being split to form a valve-casing portion adjacent the cylinder and a valve-casing portion remote therefrom which is secured to the frame; a valve rotatable in said valve-casing and adapted to open and close said port; a bushing between the valve and valve-casing extending over the split in the valve-casing and having an opening registering with said port.

9. In an engine; a frame; a member comprising a cylinder longitudinally movable relatively to the frame and comprising also a one-piece valve-casing having a port communicating with the cylinder and being split to form a valve-casing portion adjacent the cylinder and another valve-casing portion which is secured to the frame, the cylinder and valve-casing portions having a contin-

uous water jacket formed in said member; a valve rotatable in said valve-casing and adapted to open and close said port; a bushing between the valve and valve-casing extending over the split in the valve-casing and having an opening registering with said port.

10. In an engine; a frame; a member comprising a cylinder longitudinally movable relatively to the frame in a bearing thereon and comprising also a one-piece split valve-casing secured to the frame and having a port communicating with the cylinder, said member having a resilient portion intermediate the cylinder and the valve-casing; a valve rotatable in said valve-casing and adapted to open and close said port.

11. In an engine; a frame; a member comprising a cylinder longitudinally movable relatively to the frame in a bearing thereon and comprising also a one-piece split valve-casing secured to the frame and having a port communicating with the cylinder, said member being reduced in cross section intermediate the cylinder and the valve-casing; a valve rotatable in said valve-casing and adapted to open and close said port.

In testimony whereof I have hereunto set my hand at Grand Rapids, Michigan, this 15th day of June, 1921.

JOHN R. WARREN.
